DIFFUSED HEAT RADIATION APPARATUS OR OVEN.

APPLICATION FILED APR. 18, 1921.

Patented Mar. 14, 1922.

2 SHEETS—SHEET 2.

UNITED STATES PATENT OFFICE.

DAVID GUELBAUM, OF SYRACUSE, NEW YORK.

DIFFUSED-HEAT-RADIATION APPARATUS OR OVEN.

1,409,293.

Specification of Letters Patent. Patented Mar. 14, 1922.

Application filed April 18, 1921. Serial No. 462,371.

To all whom it may concern:

Be it known that I, DAVID GUELBAUM, a citizen of the United States, and a resident of Syracuse, in the county of Onondaga and 5 State of New York, have invented a certain new and useful Diffused-Heat-Radiation Apparatus or Oven, of which the following is a specification.

This invention of a diffused heat radi- 10 ation apparatus or oven, for industrial and domestic service, such as evaporating, drying, hot air circulation cooking, baking, etc., has for its object the more perfect, efficient and convenient production of the above pro- 15 cesses, on a large or small scale, with considerable saving in time and fuel.

The design of my diffused heat radiation apparatus or oven is based on a special cor- 20 olary to one of the basic thermal proper- ties of bodies, namely:

The thermal property.—In a system of bodies of different temperatures heat moves from the high temperature bodies to the low temperature ones, by radiation, as well as 25 by direct conduction.

The corollary.—If the outer surface of a hollow metal ball be thoroughly insulated by non-conducting covering, so that no heat could pass from it outside, then, a body sus- 30 pended inside such a ball will receive, by radiation, all the heat imparted to that ball and diffused over its interior surface.

Heat transmission by such diffused ra- 35 diation method possesses the following ad- vantages over all other methods now in practice:

1. The heat is simultaneously transmitted all over the surface of the body to be heated.

2. The heated body has no contact with 40 the combustion gases, hence no dirt, no soot, no corrosion.

3. Experiment shows that heat transmis- 45 sion over the whole surface of a heated body by such a method of diffused radiation takes place with greater velocity and penetrabil- ity than by direct contact with high tem- perature combustion gases of but a portion 50 of the surface of the body to be heated, as is now the common practice.

50 My invention comprises the above set forth novel features, embodied in the com- binations and constructions hereinafter set forth and claimed, and as shown on the accom- 55 panying drawings, in which like charac- ters designate the same corresponding parts in all the views.

Fig. 1 shows a sectional elevation of my diffused heat radiation apparatus.

Fig. 2 shows a top view of the air shutter plate on top of the apparatus. 60

Fig. 3 is a top view of the central bracket supporting the insulating jacket.

Fig. 4 is a cross section of the vapor outlet valve at top of the apparatus.

Fig. 5 shows a top view of said vapor out- 65 let valve.

Fig. 6 shows a top view of the lifting handles of the apparatus.

Fig. 7 shows a sectional elevation and top view of the supporting lugs and pins of the 70 apparatus.

Fig. 8 shows a fractional top view of the carrier gratings inside the apparatus and the way they are supported.

Fig. 9 shows a cross section of the ther- 75 mometer casing on top of the apparatus.

Fig. 10 shows the bottom view of my ap- paratus.

Fig. 11 shows a sectional elevation of the ring and base of my apparatus provided 80 with light sheet metal insulating jackets instead of cast on ones.

Fig. 12 shows a sectional elevation of an insulated pan for the apparatus to rest on for preserving its heat after the heating has 85 been completed.

Fig. 13 shows a sectional elevation of a simplified form of my apparatus with a com- mon frying pan used as a heat absorbing base. 90

Fig. 14 shows an enlarged view in section of the thermometer bottom with its adjust- ing wire, on top of the apparatus.

My apparatus or oven consists of three 95 essential parts, forming combinedly a closed radiation chamber, namely:

1. A heat absorbing base, which receives heat direct from the prime source, the combustion gases, and transmits it further in the form of diffused heat all over the in- 100 terior surface of the closed radiation chamber.

2. One or more intermediate extension rings or compartments.

3. The upper dome provided with a cen- 105 tral vapor outlet, hot air circulation device and a temperature indicator.

As seen on Fig. 1 the heat absorbing base consists of the preferably tapered ring 1 with the closed, preferably curved, bottom 110 2 and the cast on or attached to jacket 3, with the space between closed at top and

bottom by means of the cast on or attached to plate 4—5, and filled up with heat insulating composition. The sheet metal plate 5 is fastened to the bottom of the ring 5 with screws (not shown).

The curved bottom 2 is provided with a number of the heat absorbing webs 6, preferably tapered, as shown in elevation on Fig. 1 and in plan on Fig. 10 Sheet 2.

10 These webs are shown on Fig. 1 as resting on a closed high temperature gas burner, described in my pat. application Ser. No. 435,185. But any burner, or a plain coal and wood fire, may be used as the prime 15 source of heat.

On top of the heat absorber rests freely the extension ring 7, with the cast on or attached to jacket 8, with the space between closed at top and bottom by means of the 20 attached to or cast on plates 9—10, and filled up with heat insulating composition. The sheet metal plate 9 is here shown as sprung in into dove tailed grooves.

One only extension ring or compartment 25 is shown on Fig. 1; but there may be inserted as many as desired.

On top of the extension rings rests freely the dome 11 with the bottom flange 12 and the cone top 13, surrounded by the two concentric light sheet metal jackets 14—15 and the two top cover jackets 16—17, with the space between these jackets filled up with heat insulating composition.

All three, the absorber, extension ring and 35 dome, are provided with the overlapping flange 18 for their mutual correct centering when assembled.

They are also provided each with the two handles 19, shown in section on Fig. 1 and in 40 plan on Fig. 6, by which each part of the apparatus can be lifted and replaced as needed. The slots in these handles serve for passing a belt through to carry the apparatus within its ensemble, in case of travelling or camping.

In addition to its two handles 19 the absorbing base is also provided with the lugs 20, shown on Fig. 7 in section and in plan, of which there are four. These lugs hold the pins 21 set screwed at any position and serving as supporting legs of adjustable height, when wanted.

The extension rings are provided with the four rows of pegs 22, which may be cast on 55 direct, or four continuous strips may be cast on and afterwards grooved out into pegs.

These pegs carry the grating 23, consisting of light sheet metal strips notched in half in half, as shown in section on Fig. 1 and fractionally in plan on Fig. 8.

On this grating is placed the container or utensil to be heated, which thus may be raised or lowered together with the grating, as needed.

65 Likewise, the absorbing base is provided

with the cast on pegs 24—25 and the movable grating 26, as shown on Fig. 1, for supporting a container or utensil, which, according to the principle of diffused heat radiation, must not be in contact with the interior surface of the radiation chamber, hence cannot be placed directly on the bottom of the absorbing base.

The dome at its top terminates with the flanged nozzle 27 extending higher up to 27' 70 above its flange 28. On this flange 28 rests the central bracket serving as an air inlet valve 29 with its horizontal flange 33, shown in section on Fig. 1 and in plan on Fig. 3. Its upper inclined flange 30 supports the 80 cover jacket 16 held in place by the bent cover 34, while its lower inclined flange 31 with the webs 32 support the cover jacket 17 and together close up the insulation space between the concentric jackets 16—17.

The upper horizontal flange 33 of the air inlet valve resting on the flange 28 of the dome nozzle is provided with four openings for air inlet, as shown on Figs. 1—3.

Over these air openings revolves the air 90 shutter plate 35, shown in section on Fig. 1 and in plan on Fig. 2. By turning the air shutter 35 one way or the other, the air inlets in the flange 33 are closed or opened as much as desired. The movement of the air 95 shutter plate 35 is limited by a groove in the plate engaging a pin, as indicated on Fig. 2.

The entering outside air traverses the narrow concentric space between the dome walls 100 13—11 and the jackets 17—15, gets heated and is drawn into the interior of the dome through the numerous slots 36 at the bottom of the dome, spreads over the dried, baked or toasted product inside and is carried off 105 together with the vapors through the four longitudinal slots in the top nozzle 27'.

Around the top nozzle 27' above its flange 28 rotates the vapor outlet sleeve or valve 37, having four slots like those in the top 110 nozzle 27', as shown on Figs. 1—4—5. To prevent the vapor shooting out radially through these slots, they are enclosed by the protecting shields 38 cast on or attached to the sleeve 37.

By turning the vapor valve 37 one way or the other, the slots in the top nozzle 27' are closed or opened as much as desired. The movement of the valve is limited by the pin and groove, shown on Figs. 1—5.

The rings 39 are washers taking up the friction in the turning of the air shutter plate 35 and the valve 37.

The top nozzle 27' of the dome is provided with a thermometer of unbreakable construction, giving the exact temperature of the escaping vapors and of the dome interior at its top.

As shown on Figs. 1 and 9 the glass pipe 40 containing the mercury column is encased 130

in the metal frame 41 with the scale plate 42. The frame 41 terminates at its bottom into the hub 43 securely screwed into the top of the nozzle 27'. Into the hub 43 is screwed in 5 the fitting piece 44 with its extension 44' reaching downward into the metallic mercury well 45 which is screwed onto the fitting 44.

Into the top of the fitting 44 is tightly 10 fitted in, or cemented in, the bottom of the glass pipe 40; below it the bore of the fitting 44 is the same as that of the glass pipe.

The volume of the mercury within the metallic well 45 is adjusted to suit the scale 15 plate calibration for the required temperature limits by adjusting the length of a wire wound on the dipped into the well extension fitting 44' as shown on Fig. 14.

On Fig. 11, Sheet 2, the absorbing base 20 and the extension ring are shown provided with light sheet metal jackets, instead of cast on ones. The insulating composition is introduced through the holes shown in the top flanges.

Fig. 12, Sheet 2, shows an insulator base 25 for use as an accessory part of the radiation apparatus in domestic service. Its outer construction is the same as that of the absorbing base shown on Fig. 1; internally it 30 has a closed bottom cast on and a closed top by a sheet metal plate sprung into a dovetail groove with the space between filled up with insulation composition.

After the desired temperature within the 35 radiation chamber has been reached and lasted for a while, the burner may be replaced by the insulator base Fig. 11 which insulates the bottom of the apparatus, and the interior contents will retain that temperature for many hours, as in a fireless 40 cooker.

Fig. 13, Sheet 2, shows the radiation apparatus as adopted for simplified home service. The thermometer is replaced by a 45 plug; the air inlet valve with the interior jacket, provided for hot air circulation, are dispensed with, and the special heat absorbing base is replaced by the common frying pan.

In order to adapt the top of the latter to 50 the extension ring and the dome bottoms, the flanged sheet metal plate ring 46 is fitted to the top of the common frying pan, as shown. The outer flange of the plate is notched out 55 at 47 to clear the frying pan handle 48.

To prevent heat dissipation from the outer side surface of the frying pan the bent bottom plate 49 is joined to the top plate 46, as 60 shown, and fastened with a few screws.

The air space between the plates 46 and 49 65 may be left empty, or may be filled up with insulating composition. The grating 50, of same construction as shown on Fig. 8, rests with its four corners on the tapered sides of 70 the frying pan.

Placed over a burner or a plain fire such a jacketed frying pan with the dome and extension rings on top will do all the cooking and baking required. Placed after a while over an asbestos board or some other insulating material it will reserve heat like a fireless cooker. 70

In addition to the previously enumerated basic advantages of heat transmission by diffused radiation for industrial service, its. 75 application in my apparatus to domestic service for cooking, baking, etc., has still advantages:

What I claim is:

1. A diffused heat radiation apparatus or 80 oven, comprising a heat absorbing base having a closed ribbed bottom and provided with a heat insulating jacket, an extension ring provided with an over lapping flange at its bottom resting on top of said base and 85 having an insulating jacket outside and carrier gratings inside, a dome with an over lapping flange at its bottom resting on top of said extension ring and terminating at its top with a vapor outlet nozzle and provided 90 with double insulating jackets, a central bracket on top of said dome for supporting and securing said double insulating jackets and for air inlet, means for circulating and heating air between said dome and its inner 95 jacket, means for temperature indicating of escaping vapor, a vapor outlet regulating valve surrounding said dome nozzle, substantially as and for the purpose specified.

2. A diffused heat radiation apparatus or 100 oven, comprising a heat absorbing base having a closed bottom with heat absorbing webs and provided with an over lapping flange and a heat insulating jacket and with lifting handles and supporting lugs with adjustable setscrewed bolts and with pegs inside for holding a carrier grating for utensil support, an extension ring on top of said base, a dome on top of said extension ring with insulating jackets, means for supporting said dome jackets and for air circulation between said dome and its inner jacket, a vapor outlet regulating valve on top of said dome, substantially as and for the purpose 110 described. 115

3. A diffused heat radiation apparatus or 120 oven, comprising a heat absorbing base, and an extension ring resting on top of said base with open top and bottom and provided with an over lapping flange at its bottom with lifting handles and an insulating jacket and with carrier gratings resting on pegs inside, a dome on top of said extension ring with a central bracket and a temperature indicator, a vapor outlet valve on top of said dome, 125 substantially as and for the purpose set forth.

4. A diffused heat radiation apparatus or 130 oven, comprising a heat absorbing base, an extension ring on top of said base, and a

- dome with an over lapping flange at its bottom resting on top of said extension ring and terminating at its top into a nozzle flanged in the middle and slotted above for 5 vapor outlet with a screwed in thermometer on top and provided at its bottom flange with lifting handles and circular ribs for holding double insulating jackets with an air space between inner jacket and dome and 10 provided with slots at bottom of said air space for drawing in the heated air into the dome interior, means for securely holding said insulating jackets and for regulating the air inlet into said air space, a vapor outlet 15 regulating valve surrounding the top nozzle of said dome, substantially as and for the purpose specified.
5. A diffused heat radiation apparatus or oven, comprising a heat absorbing base, an 20 extension ring on top of said base, a dome on top of said ring provided with a vapor outlet nozzle on top flanged in the middle and with double insulating jackets forming an air space between inner jacket and dome, 25 and a central bracket comprising a sleeve with an inside flange resting on top of said dome nozzle flange and provided with air

inlet openings and an air shutter plate on top leading to said air space around the dome and having beveled flanges and ribs 30 with a beveled plate washer on top for securely holding the upper ends of said double insulating jackets around the dome, a vapor outlet valve surrounding the top nozzle of said dome, substantially as and for the purpose described.

6. A diffused heat radiation apparatus or oven, comprising a heat absorbing base, an extension ring on top of said base, a dome on top of said ring having a nozzle on top 40 flanged in the middle and slotted above supporting a thermometer and a central bracket, and a vapor outlet valve slotted and surrounding said slotted nozzle on top of the dome and provided with protecting shields 45 over said slots and with a groove and pin for limiting its rotation, substantially as and for the purpose set forth.

In testimony whereof, I have hereunto signed my name, at Syracuse, in the county 50 of Onondaga, and State of New York, this 16th day of April, 1921.

DAVID GUELBAUM.
